UNITED STATES PATENT OFFICE.

GRACE G. DURAND, OF LAKE BLUFF, ILLINOIS.

DESIGN FOR A BOTTLE.

No. 39,207.

Specification for Design.

Patented March 17, 1908.

Application filed January 29, 1908. Serial No. 413,325. Term of patent 14 years.

To all whom it may concern:

Be it known that I, GRACE G. DURAND, a citizen of the United States, residing at Lake Bluff, in the county of Lake and State of Illinois, have invented a new, original, and ornamental Design for Bottles, of which the following is a specification, reference being had to the accompanying drawing, forming part thereof.

The figure is a view in elevation of a bottle showing my new design.

I claim:

The ornamental design for bottle, as shown.

GRACE G. DURAND.
